UNITED STATES PATENT OFFICE.

WILLIAM V. THRELFALL, OF NEWTON, MASSACHUSETTS, ASSIGNOR TO THE
PETTEE MACHINE WORKS, OF SAME PLACE.

REVOLVING-FLAT CARDING-ENGINE.

SPECIFICATION forming part of Letters Patent No. 620,089, dated February 21, 1899.
Application filed November 16, 1896. Serial No. 612,198. (No model.)

To all whom it may concern:

Be it known that I, WILLIAM V. THRELFALL, a citizen of the United States, residing at Newton, in the county of Middlesex and State of Massachusetts, have invented a new and useful Improvement in Revolving-Flat Carding-Engines, of which the following is a full, clear, and exact description, reference being had to the accompanying drawings, forming a part of this specification, in explaining its nature.

The invention relates especially to a licker-in screen having an outer end or nose, which is so shaped or arranged in relation to the remainder of the screen and to the licker-in as to provide an entrance or passage between its upper surface or bars and the licker-in, which preferably gradually decreases in height, and also means whereby the said nose is adjustable upon the remainder of the screen both horizontally and in relation to the licker-in, whereby this space or passage is varied in height and length. The nose may be supported by the main section of the licker-in screen upon which it may be adjustable or upon an independent support upon which it may be adjustable. I have shown the first-named construction. The main section of the licker-in screen may be adjustable with and upon and attached to the main screen, as described in the application of Charles Mills and Loren W. Penney, No. 576,396, filed January 22, 1896, or it may be adjustable upon an independent support. I have represented in the drawings the first-named construction and consider it the more desirable one, because it provides means whereby the licker-in screen and the nose of the licker-in screen may be simultaneously adjusted with the main-cylinder screen and by the adjusting devices which are used in adjusting the main-cylinder screen.

In the drawings, Figure 1 is a view in vertical longitudinal section and in elevation of enough of a revolving-flat carding-engine to illustrate the invention. Fig. 2 is a view in vertical section upon the dotted line 2 2 of Fig. 1. Fig. 3 is a view in perspective of the licker-in screen, representing also in dotted outline a portion of the main-cylinder screen.

Fig. 4 is a view in vertical section of the screen upon the dotted line 4 4 of Fig. 3.

A is the licker-in; B, the main cylinder; C, the main-cylinder screen; E E', the motor-knives. The licker-in screen has two sections—namely, the main section d and the toe or rear section d'. The licker-in screen D is represented as attached to the flanges c of the main-cylinder screen in a manner to permit of the adjustment of its upper surface in respect to the circumference of the licker-in and being attached to the main-cylinder screen is adjustable with it. The devices for securing it to the main-cylinder screen and for adjusting it thereon are fully described in the said application, and the devices for adjusting the main-cylinder screen and thereby the licker-in screen are also fully set forth in said application. The licker-in screen of said application had its entire upper surface shaped or curved throughout to the curve of the licker-in roll, and there was no provision for establishing a passage or space between its rear end and the licker-in gradually decreasing in height. To enable this passage or space to be formed, I have made the screen in the two parts d d', as above specified, and have attached the part d' to the part d by means which enable it to be adjusted thereon to vary the position of its upper surface in relation to the licker-in. The section d comprises the side plates d², the central plate d³, the upper curved plate d⁴, which is attached to the end plates and to the central plate, and the ties d⁵, which connect the end and central plates and strengthen the construction. The section d' of the licker-in screen has the end plates d⁶ and the central plate d⁷. The end plates are connected by the hollow bars d⁸, forming a grating. The end plates d⁶ have backward extensions provided with recesses or slots d⁹, and they are formed to lap upon the outer sides of the end plates d² of the screen-section d. The central plate d⁷ has the backward extension d¹⁰, which laps upon the central plate d³, and it has the slot or recess d¹¹. The devices attaching these backward extensions of the end plates and central plate of the nose to the corresponding plates of the main section are of a char-

acter to provide for the adjustments of the nose of the screen in relation to the main section thereof both toward and from the same and also toward and from the licker-in upon an arc. These devices also provide means whereby the nose may be so held or attached to the main section of the screen that its outer end shall be farther removed from the licker-in than its inner end, thereby providing an opening between the licker-in and the beginning of the screen, which may be of any desired height and which gradually decreases in height as it extends inward. These adjustable attaching devices preferably comprise the pivots F and the adjustable locks F'. The pivots F form the centers upon which the nose-section is adapted to be turned to vary the position of its surface in relation to the licker-in. These pivots permit the horizontal movement of the nose in relation to the part d by means of the slots d⁹. The locks F' are simply clamping-bolts upon which the plates d⁶ are moved when the bolts are released and which bolts when tightened serve to lock the nose firmly to the section d. The pivots preferably each comprise the sleeve f, which extends through a hole in the end plate d² and the slot or recess d⁹ of the end plate d⁶, and which has a flange f', which bears against the inner surface of the plate d². A bolt f², having the head f³, extends through the hole in the sleeve and receives a locking-nut f⁴ and serves, with the nut, to hold the sleeve in place.

The central plate d⁷ is adjustably attached to the central plate d³ by the bolt F², the horizontal slot d¹¹ and a vertical slot in the plate d³ providing means for adjusting the bolt. By the adjustment thus obtained by the nose of the screen a passage or space G is established between the upper surface of the nose of the screen and the licker-in, which preferably gradually decreases in height from its opening as it extends inward, and which may be varied in height by the adjustment of the nose and in length by the horizontal adjustment of the nose, and this without interfering with the adjustment of the main section d of the screen to the curve of the licker-in.

While I prefer to attach the licker-in screen to the main-cylinder screen and to adjust them simultaneously, I would say that the licker-in screen when provided with the adjustable nose may be adjustably secured to any suitable support other than the main-cylinder screen, and also that the nose d' of the licker-in screen may be carried by and adjusted upon any other support than the main section d without departing from the spirit of the invention. The outermost bar of the nose is represented as having a recess h in its under side, which covers the upper edge h' of the plate H, and thereby prevents dust and fly from readily lodging or accumulating thereon.

The advantages which arise from providing the nose with the adjustment specified

and the formation of the passage G consist in the doing away entirely or to a very large extent with the making of fly, fly being waste cotton, which it is desirable not only to save, but to prevent making, because it not only is waste when it escapes, but because it also works into the lap and deteriorates it.

It will be understood that the upper curved plate d⁸ of the licker-in screen is imperforate and that it forms a downward extension from the imperforate section x, extending from the knife-edge x' downward, forming a part of the licker-in screen, but attached to the main-cylinder screen. It will also be seen that the part d of the licker-in screen, of which the plate d⁸ is a portion, is attached to the main-cylinder screen and is adjustable thereon in a manner to permit the plate d⁸ to be set in any required position in respect to the licker-in roll. Ordinarily the main-cylinder screen and the sections x and d⁸ of the licker-in screen are set throughout their length as closely as possible to the main cylinder and to the licker-in, and the adjustment of the part d of the licker-in screen necessary for accomplishing this setting of this section of the screen or any other setting is usually performed in the first setting up of the machine, and this relation of the said section d to the main-cylinder screen is not as a rule thereafter changed.

The nose-section of licker-in screen or the part lettered d' is adjustable horizontally in relation to the section d of the licker-in screen and licker-in and also upon a vertical arc, of which the locking device F is the center. This adjustment is an adjustment which is made at the original setting up of the machine and at any other time desired and is made independent of the adjustment of the mote-knives.

In the operation of the carding-machine it will be understood that the lap is fed to the licker-in and by it opened and cleansed and fed to the main carding-cylinder and that for this operation it is desirable that there be the lap-feeding rolls or devices, the mote-knives, which operate to remove the seeds and relatively large foreign substances, and the licker-in screen, the end of which provides means for the escape of the smaller waste and of fly. Heretofore it has been impossible to regulate the escape of fly at this point, and this has been due quite largely to the fact that in order to adjust the rear end of the nose of the licker-in screen in relation to the licker-in it was also necessary to move the section d⁴ above or beyond the nose in respect to the licker-in, and this has formed a passage between the section d³ and the licker-in which has permitted a back draft from the main-cylinder screen to be established, which has caused the short staple forming the fly to be blown backward and downward into the compartment below the screen and has resulted in considerable waste, which it has been the custom to separate by a division-

plate from the worthless waste from the mote-knives. By making the nose of the licker-in screen independently adjustable it becomes possible to set the section d^4 closely to the licker-in screen throughout its length and at the point x^2 , and when so set no back current from the main cylinder prevails and there is absolutely no escape of fly.

It so happens on account of the different natures of the lap in respect to the length of the staple and in respect to the seeds and dirt contained in it that adjustment of the nose-section is necessary as well as adjustment of the mote-knives, and it is desirable that these adjustments be independent of each other, some grades or qualities of cotton requiring that the nose be set farther from the licker-in than others. The adjustment of the nose away from the licker-in also widens the space x^3 between the end x^2 of the section d^4 and the bar d^8 next it, and this is also advantageous as it permits the escape of the larger particles of dirt and waste which are generally found in the cotton, which requires such an adjustment of the nose.

It will be understood that although as a rule it is desirable that the fly be not formed as waste and that the plate d^3 be set as closely as possible to the licker-in, in some instances with certain staples it is desirable there should be a winnowing or removal of the very short staple from the lap, and when this result is desired the plate d^3 may be so set in relation to the licker-in as to provide a narrow passage between the section x and the end x^2 , which gradually increases in height to the end x^2 and which permits of enough backflow or current of air from the main cylinder screen as to take the said short staple and deposit it into the compartment below the screen; but, as above stated, this is an exceptional use, and it is mentioned for the purpose of showing the range of the invention; but for most uses it is desirable that the plate d^3 be set as closely to the licker-in as possible for the reasons above stated.

Having thus fully described my invention, I claim and desire to secure by Letters Patent of the United States—

1. The combination in a revolving-flat carding-engine of the main cylinder, the main-cylinder screen, the licker-in roll, the licker-in screen having a main or principal unperforated section d and an auxiliary section or nose d' provided with escape-openings, the said main section being attached to the main-cylinder screen, means borne by the main-cylinder screen for adjusting the licker-in screen as a whole in relation thereto, and with respect to the licker-in roll, and means carried by the main section of the licker-in screen for the independent adjustment of the said section or nose d' with respect to it and to the licker-in roll, as and for the purposes set forth.

2. The licker-in screen having a cross-bar d^8 provided with a longitudinal recess h in its

under surface in line with and covering the top of the plate H , in combination with the said plate H , as and for the purposes set forth. 70

3. The combination of the main section d of the licker-in screen comprising the end plates d^2 , the curved plate d^4 , the braces d^5 and central plate d^3 , with the independent nose or rear section d' comprising the end 75 plates d^6 , the central plate d^7 , the ribs or bars d^8 , the said end and central plates having backward extensions which lap upon the corresponding plates of the main section and devices connecting said overlapping sections 80 with the said corresponding plates of the main section, as and for the purposes described.

4. In a carding-engine the combination of the main cylinder, an adjustable main-cylinder screen, the licker-in roll, the licker-in 85 screen having a main or principal unperforated section and a supplemental section or nose provided with escape-openings, the said licker-in screen being attached to the main-cylinder screen to be adjustable therewith, means borne by the main-cylinder screen for independently adjusting the licker-in screen as a whole in relation to it and with respect to the licker-in roll and additional means carried by the main section of the 95 licker-in screen for the independent adjustment of the said section or nose with respect to it, the main-cylinder screen and the licker-in roll, as and for the purposes set forth.

5. In a revolving-flat carding-engine the 100 combination of the main cylinder, an adjustable main-cylinder screen, the licker-in roll, the licker-in screen comprising a wide, unperforated section d and a relatively narrow supplemental section or nose d' provided with 105 openings, the said main and auxiliary sections being attached to the main-cylinder screen to be adjustable therewith, means borne by the main-cylinder screen for adjusting both sections of the licker-in screen as a whole in 110 relation thereto and with respect to the licker-in roll, and means for the independent adjustment of the said supplemental section or nose d' with respect to the main unperforated section, the main-cylinder screen and the 115 licker-in roll, as and for the purposes set forth.

6. The combination in a carding-engine of the licker-in roll, the adjustable main section d of the licker-in screen, the independently-adjustable end d' of the licker-in screen, the 120 mote-knives E, E' and the vertical plate H , as and for the purposes set forth.

7. The combination in a revolving-flat carding-engine of the main cylinder, the main-cylinder screen, the licker-in roll, the licker-in 125 screen consisting of a main unperforated section d and a relatively narrow supplemental section or nose d' provided with openings, the said main section being attached to the main-cylinder screen and extending to or very 130 nearly to a perpendicular line drawn through the center of the licker-in roll, means borne by the main-cylinder screen for adjusting both sections of the licker-in screen as a whole

in relation thereto and with respect to the licker-in roll and means for the independent adjustment of the said section or nose d' with respect to it and the licker-in roll.

5 8. The combination in a carding-engine of the main section of the licker-in screen d and the nose d' having end plates d^6 shaped substantially as shown and cross-bars d^8 , the end plates having backward extensions which lap 10 upon the end plates of the main section and which are provided with the recesses d^9 and connections F, F' , as and for the purposes set forth.

9. In a revolving-flat carding-engine, the 15 combination of the main cylinder, the adjustable main-cylinder screen, the licker-in roll, the licker-in screen having a main unperforated section d and a relatively narrow supplemental section or nose d' provided with 20 openings, the said main section being attached to the main-cylinder screen, means borne by the main-cylinder screen for adjusting the licker-in screen as a whole in relation thereto and with respect to the licker-in roll, 25 means carried by the main section of the licker-in screen for the independent adjustment of the said supplemental section or nose d' with respect to it and to the licker-in roll, both of said sections of the licker-in screen being 30 adjustable with the main-cylinder screen, and independent, adjustable mote-knives, all as and for the purposes set forth.

10. The combination in a revolving-flat carding-engine of the licker-in roll, the licker-in 35 screen having a main or principal unperforated section d extending to or nearly to a

perpendicular line drawn through the licker-in roll and adjustable as a whole with respect to the licker-in roll, to vary the width of the passage between it and the licker-in roll 40 from its lower to its upper end, and a relatively narrow supplemental section or nose d' provided with openings attached to the main section of the licker-in screen to be adjustable therewith and means for independently adjusting the said supplemental section or nose with respect to the main section of the licker-in screen and the licker-in roll, all as and for the purposes set forth. 45

11. The combination in a carding-engine of 50 the section d of the licker-in screen having the curved imperforate plate d^3 , the section d' of the licker-in screen and means for varying the width of the space x^3 between the end of the plate d^3 and the first bar d^8 of the said section d' .

12. In a carding-engine the licker-in roll, independently-adjustable mote knife or knives, the licker-in screen having the imperforate plates x, d^4 and the nose d' , the plate x being 60 attached to the frame of the main-cylinder screen, the curved imperforate plate d^3 being independently adjustable in relation to the licker-in and the plate x , and the section d' being adjustable independently of the plate 65 d^3 , and the mote knife or knives, as and for the purposes set forth.

WILLIAM V. THRELFALL.
